CAP DISCHARGE DEVICE

Raymond M. Mikolay, Chicago, Ill., assignor to
Tybond Tool Engineering Company, a corpora-
tion of Illinois

Application January 16, 1950, Serial No. 138,778

6 Claims. (Cl. 46—200)

1

This invention relates to a toy noise creating device, particularly to a device for safely discharging noise making caps of the type usually used in toy cap pistols.

Prior art explosive type noise making toys designed to attract children are all too often of a type too dangerous for operation by children without close adult surveillance. Many of the safer types are often not sufficiently attractive to maintain a child's interest or are too complicated for children to operate, thus causing them to turn to the more dangerous types.

In view of the foregoing conditions, it is a principal object of this invention to provide a toy noise creating device which is absolutely safe to operate, easily loaded and at the same time attractive in appearance.

Still another object of the present invention is to provide a novel cap discharge device in which the discharge action is not performed directly in the hands of the operator.

A still further object of the present invention is to provide a novel cap discharge device which will discharge only upon impact with a hard surface, thus preventing it from discharging if a person is hit accidentally.

An additional object is to provide a toy cap discharge device which can be discharged at a point remote from the operator.

The novel features which I believe to be characteristic of my invention are set forth with particularity in the appended claims. My invention, however, both as to its organization and method of operation, together with further objects and advantages thereof, may best be understood by reference to the following description taken in connection with the accompanying drawing, in which:

Figure 1 is a perspective view of a rocket or bomb shaped cap discharge device embodying the principles of the present invention;

Figure 2 is a partial side view of the device showing the manner in which a cap is loaded therein;

Figure 3 is a cross-section of the device taken on line 3—3 of Figure 2;

Figure 4 is a top plan view of the nose-piece of the device;

Figure 5 is a cross sectional elevation view of the nose-piece as taken on line 5—5 of Figure 4;

Figure 6 is a top plan view of the center-piece;

Figure 7 is a cross sectional view of the center-piece as taken on line 7—7 of Figure 6.

In greater detail the figures illustrate a minia-

2

ture bomb-shaped toy which includes three principal parts, namely; an impact head or nose-piece 10, a center-piece 11 and a tail-piece 12. All are of such shape that they can be readily molded of plastic material of a type which can withstand a great deal of rugged handling. The nose-piece and center-piece are preferably of hard material such as Bakelite because it is between abutting flat surfaces of these elements that the cap discharge action takes place and because the nose-piece must withstand a direct impact to discharge the cap. The tail-piece, however, is not subjected to as much direct stress and therefore may be of softer material such as polyethylene or Vinylite.

The nose-piece 10 includes a hemispherically shaped tip with a relatively short cylindrical portion 15 extending back from the tip on which an anvil or flat table surface 13 is provided to establish an abutting relationship with a corresponding anvil surface 14 of the center-piece 11. As illustrated in Figure 2, it is between these surfaces 13 and 14 where the cap 16 is located for discharge. Projecting from the flat surface 13 of the nose-piece are a pair of parallel spaced wire legs 18 and 19 extending perpendicularly from the anvil or table surface 13 a distance apart slightly greater than the width of caps of the type to be loaded in the device. These wire legs 18 and 19 are parts of a U-shaped staple 20 having its bridge portions 21 embedded in the nose material during the molding process. The wire legs thus arranged provide means for establishing a resilient assembly relationship between the nose and center pieces as will be explained.

As shown in Figures 6 and 7, the center-piece 11 comprises in general a flat circular slug or disk 22 having an elongated plug or core portion 23 of relatively small diameter extending from the center of a flat surface 24 thereof. A pair of generally rectangular wings 25 projecting oppositely from the plug portion 23 have a length approximately half that of the core. They extend upwardly from the flat surface of the disk and outwardly to within a short distance of its edge, but not completely across its diameter. A pair of spaced apertures 26 a sufficient distance apart and of a size to accommodate the wire legs 18 and 19, are provided on diametrically opposite sides of the plug portion 23 in alignment at right angles to the plane of the wing extensions 25. These holes have beveled top edges which facilitate insertion of the legs therein during the assembly operations.

To assemble the nose and center pieces in

resilient relation, the wire leg members 18 and 19 are inserted in the apertures 26 until the flat surface 13 of the nose-piece abuts the table surface 14 of the center-piece. A pair of hooks 28 are then formed at the ends of the wire members. A resilient rubber-band 29 preferably having a normal inside diameter equal to the diameter of the plug portion 23, is slipped thereover to a point just above the wing projections 25. The hooks 28 are formed on the wire leg members at a level slightly below the top of the wing projections 25 so that the rubber-band 29 may be looped through each of such hooks to establish a resilient securing relation between the nose and center pieces. Thus, when a force is exerted to separate these two parts, the rubber-band acts to draw them together into a normal abutting relation. This particular arrangement of assembling the nose and center pieces has the feature of fixed radial positioning and in addition produces a force acting to draw the nose and center pieces together in such a way as to assure good contact over the entire area of the abutting surfaces.

The tail-piece of the device includes a circular cup-like housing portion 30 at the forward end which gradually decreases in size to a point where it joins a shaft-like extension 31 of relatively small diameter at the rear of the tail-piece 12. Four tailfins 33 arranged in quadrature relation are molded directly on the shaft 31. Each fin 33 is a right triangle in shape having a relatively thin cross-section and is joined to the shaft-like extension 31 along the edge defining the longer leg of the triangle.

The inner diameter of the forward part of the cup-like housing 30 is such that the disk 22 of the center-piece 11 fits snugly therein while the outer diameter of the extreme forward end has the same diameter as the cylindrical rearwardly extending portion 15 of the nose-piece. The depth of the cup-like portion 30 is just sufficient to permit seating of the upper surfaces of the projecting wings 25 on the bottom cup surface when the disk 22 is pushed approximately half way within the cup-like portion. A bore 34 is provided in the bottom of the cup-like portion 30 to accommodate the plug 23 of the center-piece in press-fit relation. The top edge of the bore is beveled to enable guiding of the plug into the bore during assembly operations. This beveled edge of the bore also provides a space within which portions of the rubber-band 29 may be disposed without being crimped when the center-piece 11 is inserted to its extreme depth in the bottom of the cup-like housing 30. To further facilitate insertion of the plug 23 within the bore 34, the end of the plug is also beveled to guide it to the center of the bore.

In loading the present device, the nose-piece 10 is withdrawn to the full extent allowed by the length of the wire leg members 18 and 19, that is, it is withdrawn until the hooks 28 hit the disk 22. A cap 16 is then inserted between the nose-piece surface 13 and the flat surface 14 of the disk. The cap is aligned centrally between the wire legs 18 and 19 of the staple 20, whereupon the nose-piece 10 is released to clamp and substantially surround the cap 16 for discharge.

To discharge the cap, the device is thrown into the air in a location where it can drop to a hard surface. Because of the particular design illustrated, the nose-piece of the device normally takes the lead in its path of travel and causes the tip to take the full impact of the drop when

it hits the hard surface. The force of impact naturally is transmitted to the cap in effect like a hammer blow, and is effective in discharging the explosive matter contained therein with a loud report. Scrap particles of the discharged cap are removed merely by letting them drop away during reloading operations when the head and center pieces are again separated.

Although a preferable form for establishing a resilient assembly relation between the nose and center pieces has been described herein, it will be readily apparent to those skilled in the art that the resilient association also may be obtained by modification of such details. For example, the wire members presently extending from the nose-piece might be molded into the center-piece and resiliently engaged by a rubber-band mounted on the nose-piece, or notches might be placed on the core of the tail-piece instead of using wings for engagement of the rubber-band. The rubber-band may also be replaced by spring means for establishing the resilient relation.

While I have shown a particular embodiment of my invention, it will, of course, be understood that I do not wish to be limited thereto since many modifications, both in the elements employed and their cooperative structure, may be made without departing from the spirit and scope of my invention. I contemplate, by the appended claims to cover any such modifications as fall within the true spirit and scope of my invention.

I claim as my invention:

1. A cap discharge device comprising an impact head of generally hemispherical shape, a center-piece comprising a disk having a plug portion extending from one of its flat surfaces, a pair of flat surfaces on said impact head and center-piece disposed in abutting relation, a hook member extending from the flat surface of said head, said hook member extending through said disk portion, and slightly beyond said one surface, a resilient connecting member positioned on said plug portion and engaging said hook member to draw said head and center pieces together in separable relation at their abutting surfaces between which a cap may be inserted, a tail-piece comprising a cup-like housing portion and a fin type tail portion, said housing portion having an outer diameter equal to that of said impact head and an inner diameter equal to the diameter of said disk to permit a snug fit of said disk therein for at least part of its thickness, said housing portion also having a bore in the bottom thereof to accommodate the plug portion of said center-piece in press fit relation, thereby to securely hold the elements of said device in assembled relation.

2. A cap discharge device comprising an impact head, a center-piece comprising a disk having a plug portion extending from one of its flat surfaces, a pair of flat surfaces on said head and center-piece, disposed in abutting relation, a pair of spaced parallel leg members extending perpendicularly from the flat surface of said head, a connecting member on said center-piece resiliently engaging said leg members to separably draw said head and center pieces together at their abutting surfaces to permit a cap to be inserted, and clamped therebetween, a tail-piece comprising a cup-like housing portion and a fin type tail portion, said housing portion having dimensions permitting a snug accommodation of at least a portion of said disk, said center-piece plug portion being accommodated in press fit relation in a bore provided in said housing por-

tion thereby to securely hold the elements of said device in assembled relation.

3. A cap discharge device comprising an impact head having a flat surface portion, a center-piece having a flat surface on one side matching that on said impact head and a projecting portion on the opposite side thereof, the flat surfaces on said head and center-piece being disposed in abutting relation, at least a pair of spaced leg members fixed with and extending from said head, a connecting member associated with the projecting portion of said center-piece resiliently engaging said leg members to separably draw said head and center pieces together at their abutting surfaces to permit a cap to be inserted and clamped therebetween, and a tail-piece fixedly secured to said center-piece comprising a cup-like housing portion and a fin type tail portion, said housing portion enclosing the raised portion of said center-piece as well as said connecting member and the portions of said legs engaged thereby, while said tail portion is arranged to cause the head of said device to take the lead in the path of travel when said device is thrown into space.

4. A cap discharge device comprising an impact head, a center-piece having a raised portion on one side thereof, a pair of flat surfaces on said head and center-piece disposed in abutting relation, a pair of spaced parallel leg members extending perpendicularly from the flat surface of said head, a pair of apertures in said center-piece corresponding to said leg members and through which said leg members extend, the raised portion on said center-piece lying between said leg members, a resilient band type connecting member extending across said raised portion and engaging said leg members to separably draw said head and center pieces together at their abutting surfaces to permit a cap to be inserted and clamped therebetween, and a tail-piece fixedly secured to said center-piece comprising a cup-like housing portion and a fin type tail portion, said housing portion enclosing the raised portion of said center-piece as well as said connecting member and the portions of said legs engaged thereby, while said tail portion is arranged to cause the head of said device to take the lead in the path of travel when said device is thrown into space.

5. A cap discharge device comprising an impact head, a center-piece, said impact head and center-piece each having a flat-surface portion disposed to permit establishment of an abutting relation at said surfaces, a pair of spaced leg members fixed with and extending from said impact head, a pair of apertures in said center-piece corresponding to said leg members and through which said leg members extend, said

center-piece having a portion disposed between said legs and projecting in a direction away from said impact head, said portion projecting a distance at least as far as to the ends of said legs under the condition of said impact head and center-piece being in abutting relation, a connecting member comprising an elastic band extending across the end of said projecting portion and securingly engaging said leg members to hold said head and center-piece together in resiliently separable relation, thereby adapting said head and center-piece to receive and clamp a percussion cap between their abutting surfaces, and a tail-piece secured to said center-piece having a housing portion enclosing the projecting portion of said center-piece as well as the elastic band and the portions of said legs engaged thereby.

6. A cap discharge device comprising an impact head, a center-piece, said impact head and center-piece each having a flat-surface portion disposed to permit establishment of an abutting relation at said surfaces, a pair of spaced leg members fixed with and extending from said impact head, each of said leg members having a hook formed generally at the end thereof, a pair of apertures in said center-piece corresponding to said leg members and through which said leg members extend, said center-piece having a portion disposed between said legs and projecting in a direction away from said impact head, said portion projecting a distance at least as far as to the ends of said legs under the condition of said impact head and center-piece being in abutting relation, an elastic band extending across the end of said projecting portion and securingly engaging the hooks of said leg members to hold said head and center-piece together in resiliently separable relation, thereby adapting said head and center-piece to receive and clamp a percussion cap between their abutting surfaces, and a tail-piece secured to said center-piece having a housing portion enclosing the projecting portion of said center-piece as well as the elastic band and the portions of said legs engaged thereby.
